SOLDERLESS ELECTRICAL TERMINAL

Raymond N. Rowe, Plainville, Conn., assignor to
The Trumbull Electric Manufacturing Company,
Plainville, Conn., a corporation of Connecticut

Application March 3, 1934, Serial No. 713,789

5 Claims. (Cl. 173—269)

My invention relates to electrical wire connecting or terminal devices of the solderless type.

One object is to provide a rugged construction capable of accommodating cables of the stranded or multiple wire type.

5 A special object is to provide a construction of this character which will provide a positive interlock and an effective electrical connection without the use of solder.

10 Another object is to provide a terminal device to which a cable end may be readily attached or removed when desired.

In carrying out the invention I provide a rugged and rigid terminal member having a recess or 15 passage for the reception of the end of the cable. At right angles to this recess is arranged another passage or recess containing a movable clamping saddle and a clamp screw. The lower face 20 of the saddle and the bottom of the recess may be provided with supplemental means for interlocking with the cable end to hold it more securely in place.

Fig. 1 is a perspective view of the parts of one form of my invention.

25 Fig. 2 is a longitudinal sectional view of the same.

Fig. 3 is a transverse sectional view showing a cable end held in place.

30 Fig. 4 is a longitudinal sectional view partially on the plane of the line 4—4 of Fig. 2.

Fig. 5 is a detailed view of the underside of the clamping saddle.

35 The device preferably consists of a supporting plate or base 7 with a body or housing 8 integral therewith and provided with a recess or socket 9 for the end of the cable. Another passage 10 at right angles to the cable passage is screw threaded and of somewhat larger diameter than the passage 9.

40 The clamping saddle 11 is adapted to be inserted into the recess 10 and has arms 12 for embracing the sides of the cable or wire.

45 The clamp screw or nut 14 fits into the threaded passage 10 and is rotatable against the upper face of the saddle 11 to force the saddle downwardly against the cable end 15 so as to compact the wires and spread the cable end into the position shown in Fig. 3. The bottom of the recess 9 may be provided with a depression 16 for 50 kinking and thus more securely holding the wire. An additional rib or ribs 17 may also be provided in the bottom of the cable passage 9 to interlock with the wires of the cable end.

55 I also preferably provide one or more ribs 18 in the under face of the saddle to cooperate with

the upper part of the cable end to furnish additional interlock and security. The passage 9 preferably extends inward beyond the passage 10 to form a pocket 19 for the tip end of the cable so that when the saddle 11 bites into the sides and top of the wires the tips of the wires can serve as additional interlocking members to prevent the accidental withdrawal of the cable.

5 By forming the nut 14 with an opening 20 the saddle member can be seen through the opening 10 so that the operator will know when the nut is seated against the upper end of the saddle. Preferably the housing and nut are so designed that the nut is completely out of sight when properly seated and the housing has only a smooth upper 15 surface which affords no dangerous projecting angles.

The laterally offset portions or side bays 13 in the housing recess shown in Figs. 2, 3 and 4 enable the saddle side portions or arms 12 to readily get outside of the wire strands, which is an important advantage not possessed by constructions in which an arcuate saddle moves down between side walls which are not provided with such side bays or offset portions in the housing recess. Having the side arms 12 laterally outside 20 of the conductor strands in effect causes the side portions of the saddle to move radially inward as well as downward in effecting a clamping action 25 on the wire.

30 Another feature is the tapered shape to these offset portions of the housing recess. As shown in Figs. 2 and 4 at the height of the median plane on which Fig. 4 is taken, these offset bays are comparatively narrow with the result there is less tendency for the strands to be spread laterally into a narrow recess than there is for them to spread under compression into a space which is wider longitudinally of the wire. The spreading tendency is a maximum at the height of the 35 median plane 4—4 in Fig. 2 where the offset bays are quite narrow, yet wide enough for the saddle side arms 12 to slide down outside the wire. The saddle side arms are shown as being similarly tapered to conform to the tapered recesses 13. 40 From Fig. 2 it may be seen that the saddle arms 12 extend below the median plane 4—4 before substantial pressure is applied to the saddle.

45 Another feature includes the stops shown in Fig. 3 to limit downward movement of the saddle. The saddle being substantially circular in plan view as shown in Figs. 1 and 5 is adapted to the tapered shape of the offset base. Having the sides 50 laterally outside of the conductor strands in effect enables at least some of the side portions 55

of the saddle to be easily wedged between the conductor strands and the outer walls of said side bays in effecting a clamping action on the wire.

I claim:

- 5 1. An electrical connector including a housing provided with a recess in which a stranded conductor is adapted to be received, said recess having side bays, clamping means for a conductor consisting of a saddle having a concave surface adapted to fit around and laterally outside the conductor, said saddle having side arms adapted to extend over opposite sides of the conductor and into said side bays, the end portions of said side arms within said side bays being 10 capable of movement to below the axis of said recess whereby said inner end portions of the side arms may be easily wedged between the conductor strands and the outer walls of said side bays, and a nut rotatable independently of 15 said saddle for applying pressure thereto.
2. An electrical connector including a housing provided with a recess in which a stranded conductor is adapted to be received, clamping means for a conductor consisting of a saddle having a concave surface adapted to fit around and laterally outside the conductor, said saddle having side portions adapted to extend over opposite sides of the conductor, said recess being provided with laterally offset portions on opposite sides in 20 which said saddle side portions may slide as the conductor is compressed by said saddle, and a nut rotatable independently of said saddle for applying pressure thereto, the laterally offset opposite portions of the housing recess being tapered 25 away from the nut and extending at least substantially as far as an axial central plane through said recess, and the saddle side portions also being substantially similarly tapered.
3. An electrical connector including a housing 30 provided with a recess in which a stranded conductor is adapted to be received, clamping means for a conductor consisting of a saddle having a concave surface adapted to fit around and laterally outside the conductor, said saddle having side portions adapted to extend over opposite sides of the conductor, said recess being provided with laterally offset portions on opposite sides in which 35 said saddle side portions may slide as the conductor is compressed by said saddle, and a nut rotatable independently of said saddle for applying pressure thereto, the laterally offset opposite portions of the housing recess being tapered away from the nut and extending at least substantially as far as an axial central plane through said recess, and the saddle side portions also being substantially similarly tapered, the concave surface of the saddle being provided with conductor gripping ridges intermediate its opposite tapered portions, and the side of the housing recess opposite said saddle being also provided 40 with complementary conductor gripping ridges.
4. An electrical connector including a housing provided with a recess having side bays, a saddle of substantial circular shape and provided with 10 tapered side arms adapted to slide within said side bays and extend below the axis of said recess to enclose and compress some of the sides of a stranded conductor of nearly the size of said recess, a recessed nut countersunk within said 15 housing when the saddle has compressed a conductor in said housing, said nut being of larger diameter than said saddle, the housing recess being substantially longer than the diameter of the saddle and at least one conductor gripping ridge 20 on said saddle intermediate said tapered side arms extending transversely of a conductor in said housing.
5. An electrical connector including a housing provided with a recess in which a stranded conductor is adapted to be received, clamping means for a conductor consisting of a saddle having a concave surface adapted to fit around and laterally outside the conductor, said saddle having side portions adapted to extend over opposite 25 sides of the conductor, said recess being provided with laterally offset portions on opposite sides in which said saddle side portions may slide as the conductor is compressed by said saddle, and a nut rotatable independently of said saddle 30 for applying pressure thereto, the laterally offset opposite portions of the housing recess being tapered away from the nut and extending at least substantially as far as an axial central plane through said recess, and the saddle side portions 35 also being substantially similarly tapered, the concave surface of the saddle being provided with conductor gripping ridges intermediate its opposite tapered portions, and the side of the housing recess opposite said saddle being also provided 40 with complementary conductor gripping ridges.

RAYMOND N. ROWE.
